William Monroe.

UNITED STATES PATENT OFFICE.

WILLIAM MUNROE, OF WEST AUBURN, MAINE.

SOLE-CUTTING MACHINE.

Specification of Letters Patent No. 25,758, dated October 11, 1859.

To all whom it may concern:

Be it known that I, W. MUNROE, of West Auburn, in the county of Androscoggin and State of Maine, have invented a new and 5 Improved Machine for Cutting Out Boot and Shoe Soles; and I do hereby declare that the following is a full, clear, and exact description of the same, reference being had to the annexed drawings, making a part of 10 this specification, in which—

Figure 1, is a side sectional view of my invention. Fig. 2, is a front view of ditto. Fig. 2, is a horizontal section of ditto taken in the line α , α , Fig. 1.

15 Similar letters of reference indicate corresponding parts in the several figures.

The invention consists in the peculiar means employed for operating the arbor and die both as regards the rotating and up 20 and down movement and the gaging or determining of the length of each movement as hereinafter set forth.

The invention further consists in a novel 25 means employed for operating a gage whereby the same at the proper time serves as a stop to insure the proper adjustment of the leather beneath the die and is removed at the proper time to permit the cut soles and refuse to be discharged from the plat- 30 form previous to each cut of the die.

To enable those skilled in the art to make and use my invention I will proceed to de- 35 scribe its construction and operation.

A, represents a platform which is sup- 35 ported at a suitable height by a framing B, and C, is a cylindrical hard wood block which is inserted in the platform A, its upper surface being "flush" with the plat- 40 form and its lower end resting on a bar or plate a , in the framing. This block is secured in proper position and prevented from casually turning by means of a set screw b . By loosening or unscrewing this set screw at any time the block C, may be 45 turned and then secured at any point. This will be fully understood by referring to Fig. 1.

D is an upright which is firmly secured to the framing B, and extends some distance 50 above it. To this upright two horizontal arms c , c , are attached one over the other in the same plane. These arms project over the platform A, and they serve as guides for a vertical arbor E, which is allowed to 55 slide freely up and down therein. The up-

per end of the arbor E, passes through an arm d , the latter fitting in a recess in the arbor and below a wooden top portion e , which extends up through a horizontal plate or bar f , attached to two upright rods g , g , 60 secured to the framing B. The arm d , is attached to a vertical rod F, which slides in its arms c , c , and in another bearing h , near its lower end. The arm d , being attached to the arbor E, the latter will be raised with 65 the rod F. This will be more particularly referred to hereafter.

In each side of the arbor E, two vertical slots i , i' , are made. These slots at each side of the arbor are in line with each other, 70 as shown clearly in Fig. 1. Each slot i , has an oblique or spiral slot j , communicating with it. These spiral slots form a communication between the lower vertical slots i , at one side of the arbor and the upper vertical slots i' , at the opposite side. 75 This will be fully understood by referring to Fig. 1, the dotted lines showing the form of the spiral slots at the back side of the arbor.

To the lower end of the arbor E, a plate G, is firmly attached. The form of this plate is plainly shown in Fig. 3. To the under side of the plate G, a similar plate H, is attached by bolts k , which are fitted in slots in the ends of plate G, see Figs. 1 and 3. To the under side of the plate H, a cutting flanch l , is attached or formed on said plate. This flanch is of the precise form designed for the soles to be cut and the flanch encompasses an opening m , in the plate H. The flanch l , and plate H, form 90 a cutting die and its operation will be presently shown.

Within the opening m , a block n , is placed. 95 This block n , corresponds in form to the flanch l , and its upper side is provided with a stem o , which passes into the lower end of the arbor F, and has a spiral spring p , 100 placed above it, as shown clearly in Fig. 1.

To the upright D, there are two horizontal elastic bars q , r , attached. These bars have each a right angular projection s , at their outer ends and these projections fit in 105 the recesses i , i' , j , and perform functions hereinafter described.

In the lower part of the framing B, a horizontal shaft I , is placed. This shaft has a driving pulley J , on its outer end and a 110 cam K , on its inner end, which acts as the

shaft I, rotates against a pin *t*, on the rod F. To the inner side of the driving pulley J, a part pinion L, is attached, the toothed portion of which as the shaft I, rotates gears 5 into a pinion M, on a shaft N, to which a strap O, is attached, said shaft also having a spiral spring P', upon it which spring has a tendency to keep a pin *u*, at the inner side of the pinion M, in contact with a bar *v*, attached to the framing B. The strap O, passes over a guide pulley *w*, at the upper end of the upright D, and also passes around a pulley *x*, in the outer end of a horizontal arm *y*, attached to the upper end of said 10 upright, the strap having a weight P', attached to its end.

To the upright D, a guide *a'*, is attached, and in this guide the upper end of a vertical arbor or shaft Q, is fitted and works. The lower end of shaft Q, is fitted in a sliding bearing *b'*, said bearing being fitted in suitable guides *c'*, attached to the upright D. The shaft Q, is allowed to turn in its bearings, and to its lower end a horizontal bar 15 R, is attached, said bar having an adjustable horizontal bar R', attached, the latter bar projecting over the platform A, and having a plate S, attached to it at right angles, the plate being attached to the bar by a set 20 screw which passes through a slot *d'*, in the plate into the bar as shown plainly in Fig. 3. The plate S, performs the function of a gage and one end of it is bent downward at right angles as shown at *e'*, Fig. 2. To 25 the inner side of bar R, a block *f'*, is attached. This bar is notched in order to form a shoulder *g'*, and an inclined surface *g''*, for a pin *h'*, on the rod F, to act upon as the latter rises and falls, see Fig. 2.

30 T, is a gage which is secured to the upper surface of the platform A, by set screws *i'*, *i''*, the latter passing through slotted arms *j'*, attached at right angles to the gage T, as shown plainly in Fig. 3.

35 The operation is as follows:—A continuous rotary movement is given the shaft I, by any convenient power, and at every revolution of the pulley J, the teeth of the part pinion L, will rotate the pinion M, of shaft N, and the strap O, will be wound on shaft N, and the weight P, elevated. Simultaneously with the raising of the weight P, the rod F, and arbor E, are raised by the 40 action of the cam K, against the pin *t*.

45 As the arbor E, rises it is rotated just one half of a revolution in consequence of the projection *s*, of bar *q*, fitting in one of the spiral slots *j*, and when the arbor E, is fully raised the projection *s*, of the elastic 50 bar *r*, passes into the upper vertical slot *i'*, and serves as a stop to the arbor so far as regards its rotating movement. At this 55 point the projection of the bar *r*, is in the upper slot *i'*, and the projection of bar *q*, in the lower slot *i'*, and when the prominent

portion of the cam K, passes the pin *t*, the arbor E, and rod F, drop by their own gravity and the flanch *l*, falls on the strip of leather U, shown in blue outline on the platform A, the flanch *l*, falling on the leather 70 directly over the block C, which is the bed. Just after the arbor E, has fallen the toothed portion of the part pinion L, passes the pinion M, and the weight P, then falls by its own gravity and strikes the arbor E, forcing 75 the flanch *l*, entirely through the leather strip U, and cutting out therefrom a sole. The flanch *l*, is prevented from sinking into the block or bed C, an unnecessary distance on account of the bar *f*, which serves as a 80 stop for the weight P, preventing the latter from acting beyond a certain distance on the arbor. As the arbor E, again rises under the action of the cam K, the sole within the flanch *l*, is retained on the block or bed 85 C, by the block *n*, which is under the pressure of the spring *p*, until the flanch *l*, is raised out of the leather strip. The block *n*, then rises with the arbor. It will be seen therefore that the block *n*, serves to free 90 or discharge the cut sole from the flanch, permitting the latter to rise without carrying the sole with it.

One side of the strip U, of leather is placed against the gage T, and the end against the 95 stop S. These parts insure the proper adjustment of the leather U. Each time the arbor E, rises the operator shoves the cut sole off the block C, the stop S, being raised to permit such result in consequence of the pin 100 *h'*, striking against the shoulder *g'*, of the block *f'*, a spring *j*, on the shaft Q, forcing down the stop when the pin *h'*, passes the shoulder *g'*, of the block *f'*. When the arbor E, falls the pin *h*, in passing over the inclined surface *g''*, of the block *f'*, forces the stop S, out from the flanch *l*, so that the stop cannot interfere with the action of the flanch. This is essential as it is necessary to have the stop quite close to the flanch in order to save as much stock as possible. The stop as it falls is thrown back to its proper position by a spring *k'*. The spring *p*, on the shaft N, turns the pin *u*, directly in contact with the bar *v*, and insures the proper 110 relative position or disposition of the shaft N, and strap O, for a succeeding operation as soon as the teeth of the part pinion have passed those of the pinion M. The block or bed C, is turned at any time as previously referred to in order to cause the block to be cut evenly by the flanch *l*, the cutters being by that means distributed over its entire surface. The flanch *l*, in consequence of the semi-rotation of the arbor E, at each upward 115 movement, cuts the soles out from the leather U, with the heels and toes alternately from either side so as to prevent as little waste of stock as possible.

I do not claim the revolving die, nor the 120

adjustable rotating bed, for they have been previously used, but,

Having thus described my invention what I claim as new and desire to secure by Letters Patent is,

1. The arrangement of the vertical slots i, i' , in the arbor E, elastic bars q, r , with their projections s , fitting respectively in said slots, the weight p , bar f , and the shafts I, N, provided respectively with the cam K, spring p' , pinion M, part pinion L, and strap O, substantially as described, to

operate the arbor F, and its die or cutting flanch l.

2. The stop S, attached to a shaft Q, provided with springs j', k' , and actuated by the pin h' , on the rod F, and the notched block f' , attached to the bar R, substantially as and for the purpose set forth.

WILLIAM MUNROE.
